UNITED STATES PATENT OFFICE.

WALTER L. SCHRODER, OF WINNECONNE, WISCONSIN, ASSIGNOR TO THE PHINNEY ENGINEERING COMPANY, OF CHILlicothe, OHIO, A CORPORATION OF OHIO.

BEAN-SNIPPING MACHINE.

1,116,930.

Specification of Letters Patent. Patented Nov. 10, 1914.

Application filed February 12, 1907. Serial No. 356,993.

To all whom it may concern:

Be it known that I, WALTER L. SCHRODER, a citizen of the United States of America, residing at Winneconne, in the county of 5 Winnebago and State of Wisconsin, have invented certain new and useful Improvements in Bean-Snipping Machines, of which the following is a specification.

This invention relates to improvements in 10 machines that are adapted to sever or remove a definite portion from both ends of an object irrespective of its length, and though the machine illustrated is designed primarily for removing the ends of bean-pods, 15 the machine as to details may be modified for other analogous uses.

A machine made in accord with my invention includes as a part thereof a hollow cylinder, the wall having apertures there- 20 through into which objects from which it is desired to remove a definite quantity from each end are fed, such objects being movable in the apertures to extend beyond the faces of the cylinder and engage cutters or knives 25 that sever the projecting ends, the cylinder being movable to bring the objects in line with the sphere of action of the knives.

In the accompanying drawings, Figure 1 is a side elevation of a machine embodying 30 my invention, the same being designed for removing snippets from the ends of the pods of beans. Fig. 2 is a plan view. Fig. 3 is an end elevation. Fig. 4 is a vertical section, of a part of the machine. Fig. 5 is a longitudinal section taken vertically 35 through the cylinder. Fig. 6 is a sectional view taken to one side of the funnels. Fig. 7 is a transverse sectional view of the object carrying cylinder and its cutters. Fig. 8 is a front elevation of one of the transverse 40 plates of the conveyer. Fig. 9 is a vertical section of the object-carrying cylinder with a modified form of cutters and object retaining plates, and Fig. 10 is a longitudinal 45 section of a part of the cylinder and adjacent parts.

The operative parts of the machine are supported by a suitably constructed frame 11, such frame having bearings for the 50 shafts of rolls about which passes an endless

conveyer 12 the frame also having bearings for a driven shaft 13. The shaft 13 has a sprocket-wheel about which passes a chain to turn the sprocket-wheel that is fast upon the shaft of one of the rolls of the conveyer. 55 Each of the side sections of the supporting frame have secured thereto cylindrical carrying rings 14, such rings having flanges 15 that extend inward and carry a hollow cylinder 16 to maintain such cylinder in a horizontal position in line with the upper surface of the conveyer.

The hollow cylinder 16 may be made up of a series of disks or rings which are bolted together and the distance between the inner 60 and outer walls is somewhat greater than the length of the objects to be carried thereby. The wall of the cylinder has there- 65 through longitudinal rows of apertures or holes 17 the diameter of the apertures being 70 somewhat greater than that of the objects to be received therein, for in use the objects fed into the apertures or perforations are movable therein as the cylinder is revolved, the objects shifting their position by gravity 75 so that one end will be presented to a knife or cutter adjacent to the inner surface of the cylinder the other end of the object being subsequently presented to another knife or 80 cutter adjacent to the outer face of the cyl- 85 nder, the knives removing from the objects a definite quantity irrespective of the length of the object, the amount removed from the body being determined by the position of gage-plates upon which the objects rest as the hollow cylinder is revolved.

In this machine for snipping beans, there is present above the endless conveyer 12 a series of longitudinal slats or bars 20, such slats being triangular in cross section 90 and spaced apart so that the beans will engage the conveyer between the slats and travel in rows toward the cylinder. The slats 20 are each secured at one end to a cross piece 21 that is fastened to the up- 95 ward extending sides 22 that are fastened to the longitudinal bars of the frame, and the ends of the slats 20 nearest the cylinder 16 are attached to an apron or curved plate 23 said plate also carrying funnels 24. The 100

plate 23 has a certain degree of resiliency and the beans are carried by the conveyer onto the plate 23 into the spouts or funnels 24; passing from the funnels into the apertures or perforations 17 through the wall of the cylinder 16.

To provide an intermittent feed or means for holding back the beans upon the continuously moving conveyer, the side pieces 22 10 are provided with swinging plates 25 the lower edge of such plates being serrated to overlie the slats and the surface of the conveyer between the slats. The plates 25 are connected to each other by a bar 26 and one 15 of the plates has side arms 27, the arms being connected to a lever 28 which is moved by a crank on the shaft 13. When the cylinder is at rest the plates 25 will be vertical and during the rotation of the cylinder they 20 are inclined so that the beans may pass beneath the plates. The gearing is organized so that the shaft 13 will make one complete revolution for each movement of the cylinder, the cylinder being advanced a distance 25 equal to the distance between the longitudinal lines of apertures 17. The construction provides means whereby the beans upon the part of the conveyer beyond the swinging plate that is nearest the cylinder are fed into 30 the funnels and therefrom into the apertures through the walls of the cylinder while the cylinder is at rest.

The hollow cylinder 16 has at one or both ends ratchet-disks 29, the teeth thereon being in the path of a pawl or pawls 30 that are attached to a lever or levers 31, the levers are raised by cranks 32, on the shaft 13, to turn the cylinder one step forward for each revolution of the drive shaft the turning 35 movement of the cylinder ceasing as soon as a longitudinal line of object carrying apertures is below the discharge ends of the funnels.

Within the hollow cylinder 16 there is a 40 gage-plate 33 upon which the ends of the beans will rest when fed into the apertures 17, and within the cylinder there is a knife 34 its cutting edge lying close to the upper face of the inner surface of the cylinder, 45 the gage and knife serve as aprons which prevent the beans passing from the apertures into the cylinder. The outer side of the cylinder is partially covered by a gage-plate 35 and by a knife 36. The gage- 50 plates and the knives or cutters may be attached to the fixed cylinder supporting rings, and one form of gage plates and cutters is shown by Figs. 9 and 10 of the drawings. The gage plates and the knives, 55 when constructed as shown by Figs. 1, 2, 3, and 7, may be attached to movable arms 37 and 38, (see Fig. 7) which cross each other, the arms being opened and closed by links 60 attached to the arms 37 and 38 and to a 65 vertically movable frame 39. The central

depending member of frame 39 may rest upon or be attached to a cam or cams 41 on the shaft 13, and as the frame is lifted by the cam the knives or cutters carried by the ends of the arms will be brought together. The gage-plates 42 and 43 are of such length that they will overlap except when the jaws are opened to their fullest extent, and when separated the snippets that have been severed by the cutters or knives will fall from the gage-plates. The knives or cutters operate below the vertical apertures through the cylinder. A trough or chute 18 is attached either to the frame 11 or to the fixed rings, the purpose of such trough being to receive the snippets which would otherwise be liable to lodge in the apertures or perforations through the lower side of the cylinder, and if desired there may be supported below the cylinder a receptacle or chute 19 to receive the snippets that are removed by the knives or cutters at the lower side or outer face of the cylinder. To one side of the center of the cylinder the frame may have receptacle 44 for the reception of the beans or other objects from which the ends have been removed.

In a machine for snipping string-beans, the beans are placed upon the endless carrier and the forward movement of the carrier in connection with the fixed slats move the beans forward in longitudinal rows, the beans that have been carried beyond the hold-back-plates are delivered into the funnels or spouts passing therefrom into the line of apertures below the funnels and to one side of the vertical center of the cylinder. The apertures through the cylinder are both longer and of greater diameter than the beans, and when the beans are fed thereto they rest upon the gage-plate that is maintained adjacent to the inner face of the cylinder. The cylinder being moved by the upward movement of the pawl brings the line of apertures and the beans that have been fed therein over the center of the cylinder, and the knives or cutters sever the projecting ends from the beans. The beans from which one of the ends have been removed are carried by the cylinder, and as the same is turned the beans will fall to the opposite ends of the apertures and rest upon either the gage-plate or the knife that is maintained adjacent to the outer face of the cylinder, and after the other ends have been severed the body portion of the beans with both ends snipped therefrom will fall from the cylinder when the apertures are moved beyond the end of the knife or cutter. In use the gages may be set to allow different quantities or lengths to project beyond the faces of the cylinder, so that the ends severed by the different knives will not necessarily be the same.

The machine illustrated may be varied as

to construction of the parts and the number of apertures and the size thereof may be varied to suit the purpose for which the machine is to be used, and the use of my invention is not limited solely to cutting off the ends of beans, for instance the essential features of my invention may be embodied in a machine for cutting the heads and the tails from fish, and for other purposes where 10 it is desired to remove definite quantities from objects that vary as to length.

Having thus set forth my invention, what I claim as new and desire to secure by Letters-Patent, is:

15 1. The combination in a device of the character set forth, of a rotatably supported hollow cylinder that is provided with longitudinal and circumferential series of object receiving apertures, and cutters operatively 20 maintained adjacent to both the inner and outer surfaces of the cylinder for the purpose of severing both ends from objects carried by the cylinder.

25 2. In a device of the character set forth, a rotatable hollow cylinder provided therethrough with both circumferential and longitudinally arranged object receiving apertures, supporting and actuating means adjacent to the inner and outer surfaces of the 30 cylinder for the cylinder, means for limiting movement of objects when in the apertures, and cutters operatively maintained adjacent to the inner and outer faces of the cylinder for successively severing the ends from objects.

35 3. In a device of the character set forth, a suitably maintained hollow body having a plurality of object receiving apertures therethrough, means for imparting an intermittent rotary movement to said hollow body, means for supporting objects partially within the apertures and means for severing from the objects the ends that project beyond the surfaces of the hollow body.

45 4. In a device of the character described, a hollow cylinder having object receiving apertures therethrough, means for rotating intermittently the cylinder, means for holding objects partially within the apertures, 50 and cutters maintained adjacent to the inner and outer faces of the cylinder.

55 5. In a device of the character set forth, a hollow cylinder having radially arranged apertures through its wall, means for intermittently rotating the cylinder, knives or cutters maintained concentric to the inner and outer faces of the cylinder, and gage-plates to limit the movement and projection of objects carried by the cylinder.

60 6. In a device of the character described, a hollow and intermittently rotated cylinder having apertures which extend through the wall of said cylinder, cutters overlying parts of the inner and outer faces of the 65 cylinder, gage-plates maintained beyond the

inner and outer faces of the cylinder and means for conveying objects into the apertures.

7. In a machine for the purpose set forth, an endless conveyer and means coöperating therewith for arranging articles longitudinally thereon, spouts or funnels into which said objects are delivered, a suitably supported and actuated cylinder having apertures therethrough, means for imparting an intermittently rotary movement to the cylinder to position a line of apertures below the funnels or spouts, means for maintaining objects partially within the apertures through the cylinder, and cutters positioned adjacent to the inner and outer walls of the cylinder for the purpose of severing the ends from the objects that are fed into the apertures of the cylinder, substantially as shown.

8. In a machine for the purpose set forth, a suitably supported object carrying cylinder having radial apertures therethrough, means for feeding objects into apertures formed through said cylinder, the object feeding means having a continuous movement, means for intermittently turning the cylinder, means for limiting the projection of the ends of objects when in the apertures through the cylinder beyond the inner and outer walls of the cylinder, cutters arranged adjacent to the inner and outer walls of the cylinder and a chute within the cylinder, for the purpose set forth.

9. In a machine for the purpose set forth, a continuously moving carrier, means for retarding the travel of objects placed thereon, spouts maintained to receive objects from the carrier and an intermittently moved cylinder having object receiving apertures therethrough, positioned so that the apertures may be brought in line with the discharge ends of the spouts, gage or stop plates maintained beyond the inner and outer faces of the cylinder, and cutters operatively arranged adjacent to the inner and outer faces of the cylinder and in closer proximity to the surfaces of the cylinder than the gage plates, substantially as shown.

10. In a machine for the purpose set forth, an endless carrier, spouts into which objects are delivered by the carrier and an intermittently turned hollow cylinder having longitudinal rows of object receiving apertures therethrough, means for limiting the projection of the objects beyond the walls of the cylinder and cutters maintained adjacent to the inner and outer faces of the cylinder the cutters being arranged to sever both ends from the objects while carried by the cylinder.

11. In a device of the character set forth, an endless object carrier having a plurality of open ended object receiving apertures therethrough, means operatively connected

130

- 1 with the object carrier to change by gravity the position of the objects carried thereby, means for limiting the movement of objects placed in the apertures beyond the ends of the apertures, and cutters adjacent to the inner and outer faces of the endless carrier.
- 5 12. In a device of the character set forth, an endless carrier having object receiving apertures therethrough, means for feeding objects into the apertures, means for limiting the projection of the objects beyond the faces of the carrier and cutters for removing from the objects both of the end portions that project beyond the endless carrier.
- 10 13. In a device for the purpose set forth, the combination of a movable object carrier, cutters maintained adjacent to the object carrier, means operatively connected with the object carrier for moving the same to effect by gravity a change of the position of the objects carried thereby to present the opposite ends of the objects to the cutters for alternately severing the ends from the objects while in engagement with the object carrier.
- 15 14. In a device of the character set forth, a movable object carrier, cutters maintained in operative relation to the object carrier, and means for effecting movement of the object carrier to change by gravity the position of the objects carried thereby; such change of position of the carrier presenting opposite ends of the objects to different cutters to cut from the objects the opposite end portions.
- 20 15. In a machine of the character set forth, an endless object carrier, means operatively connected with the object carrier to move the same so that objects carried thereby will have imparted thereto by reason of a change of position of the carrier a movement independent of the carrier, and means for successively severing the opposite ends from the objects while said objects are in engagement with the object carrier.
- 25 16. In a device for the purpose set forth, a movable object carrier constructed to maintain a plurality of objects, supporting and actuating means for the carrier organized to effect by gravity a longitudinal change of the position of the objects with respect to the carrier, means for limiting the movement of the objects, and cutters maintained in the different paths of the objects for successively severing the end portions therefrom.
- 30 17. In a machine of the character set forth, a movable object carrier having a plurality of object carrying compartments such carrier being mounted so that the position of the objects carried thereby will be changed by movement of the object carrier, cutters positioned in proximity to the ends of the compartments for removing both ends from the objects and means for limiting the

movement of the objects so that a definite amount may be removed therefrom by the cutters.

18. A machine for trimming string beans or other articles comprising an endless carrier, a plurality of object compartments constituting a part of the carrier, means for moving the carrier to effect by gravity movement of the objects in two directions longitudinally with respect to the object compartments, cutters positioned so that the opposite ends of the objects will be successively presented to the cutters, and means for limiting the projection of the objects beyond the carrier.

80 19. A machine for the purpose set forth, comprising an endless carrier having a plurality of open ended chambers, means for actuating the carrier to effect a change of the position of objects in the aforesaid chambers and the projection of the ends of the objects beyond the chambers of the carrier, cutters for removing the end portions from the intermediate part of the objects while the major portions of said objects are within the chambers and means for limiting the movement of the objects toward the cutters, whereby both ends of the objects will be removed from the objects while they are in engagement with the carrier.

95 20. A machine for the purpose set forth, comprising an endless object carrier having a plurality of object receiving compartments, said object carriers being mounted on horizontal axes, means for changing the position of the carrier upon its axes so that objects fed into the compartments will change their position and be projected beyond the carrier, means in different horizontal planes for limiting the movement of the objects beyond the carrier and cutters in the paths of the projected ends of the objects such cutters being adapted to sever the end portions from the objects.

100 21. In a string bean snipping machine, the combination of a carrier for a plurality of beans, means changing the position of the carrier upon its axes to change the position of the beans with respect to the carrier, a cutter operatively maintained to sever one of the end portions from the beans during the travel of the carrier, a second cutter for severing the opposite ends from the beans, and means beyond the carrier and the cutters for limiting the projection of the beans beyond the carrier.

110 22. In a bean snipper, the combination with a rotatable drum comprising internal radial pockets, of cutter blades arranged adjacent to both ends of said pockets, and means for feeding string beans into said pockets.

115 23. In a device of the character set forth, the combination with a movable object carrier comprising a plurality of pockets which

70

are of greater area longitudinally than transversely, of cutter blades arranged adjacent to both ends of said pockets, and means for feeding objects which have a greater length than diameter into said pockets.

24. In a device of the character set forth, the combination with a movable carrier having in line with its axis object receiving pockets, of cutter blades arranged adjacent to both ends of the pockets, and means for feeding objects into said pockets.

25. A machine for snipping beans comprising a carrier, means for projecting the ends of the beans beyond the carrier successively in opposite directions, and means for removing the projecting ends of the beans.

26. A machine for removing snips from string-beans, comprising in combination, a movable carrier, means for actuating the carrier, means for feeding string-beans to the carrier, and cutters maintained for successive engagement with opposite end portions of the beans to sever the snips therefrom while the intermediate portion of the beans are maintained by the carrier.

27. In a machine for snipping string-beans, the combination with bean feeding means, of a movable carrier having a plurality of compartments into which beans are placed by the feeding means, cutters maintained in line with the paths in which the end portions of the beans move when maintained by the carrier, the parts being organized to successively snip opposite ends from the beans.

28. In a machine of the character set forth, a movable carrier having a plurality of compartments adapted to receive and carry string-beans in movable engagement with the compartments, means for supplying string-beans to the compartments, means for moving the carrier to change the position of the string-beans, means maintained relative to the carrier for removing first one end and then the other end from the beans while the major portion of the beans are in the compartments.

29. In a device for snipping string-beans, a movable carrier having a plurality of receptacles in which string-beans may move longitudinally when the carrier is moved, means for moving the carrier, means for feeding beans into the receptacles of the carrier, means for retaining and limiting the longitudinal movement of the beans in the receptacles, and cutters maintained in such relation to the receptacles and to the retaining and limiting means as to cut the opposite end portions from the beans.

30. In a bean snipping machine, the combination with a movable carrier constructed to provide a plurality of receptacles for beans, of means for moving the carrier to

position the ends of the beans beyond the receptacles, means for feeding beans to the receptacles, means for limiting the movement of the beans in the receptacle, a cutter maintained to sever one of the ends from beans during movement of the carrier and another cutter that severs the other ends from the beans operating upon further movement of the carrier.

31. In a string bean snipper, the combination with a pair of supports, of a device for maintaining one end of a bean against one support and movable to effect the shifting of the bean from said support to the other support with the opposite end of the bean resting against the last named support, and cutters arranged to operate on the supporting end of the bean on each support.

32. In a string bean snipper, the combination with a pair of supports, of a guide for directing a bean to one of said supports with one end of the bean resting on the support, the guide being movable to shift the bean to the other support with the opposite end of the bean resting against the latter support, and cutters arranged for operation on the supporting ends of a bean.

33. In a machine of the character described, the combination of a carrier adapted to receive an article to be trimmed and having an opening, a cutter which is arranged adjacent to said opening and past which said article is moved by said carrier and the end of the article is severed by the movement of the carrier past said cutter, and means movable relatively to said carrier for confining the article for a time in said carrier during the cutting operation but permitting the escape of the severed portion after the cutting operation.

34. In a machine of the character described, the combination of a carrier adapted to receive an article to be trimmed and having an outlet, means for moving said carrier so that its outlet is depressed, a cutter arranged at the depressed end of the outlet for severing the tip of said article in the carrier, and means for confining the body of said article in said carrier but permitting the escape therefrom of the severed tip.

35. In a machine of the character described, the combination of a carrier having a pocket provided with outlets at its opposite ends and adapted to receive an article to be trimmed, means for moving the carrier so that the outlets of its pocket are depressed alternately, cutters for severing the tips at opposite ends of said article in the pocket, and means for confining the body of said article in said pocket but permitting the escape therefrom of the severed tips.

36. In a machine of the character described, the combination of a carrier hav-

ing a pocket provided with outlets at its opposite ends and adapted to receive an article to be trimmed, means for moving the carrier so that the outlets of its pocket are 5 depressed alternately, cutters arranged at the depressed ends of the pocket for severing the tips at opposite ends of said article in the pocket, and means for confining the body of said article in said pocket but permitting the escape therefrom of the severed 10 tips.

37. In a machine of the character described, the combination of a carrier having a pocket provided with outlets at its opposite ends and adapted to receive the article 15 to be trimmed, means for moving said carrier so as to cause the article in the pocket to slide toward its depressed end by gravity, means for limiting the movement of said 20 article toward the depressed end of the pocket, and means for trimming off that tip of the article which has been depressed.

38. In a machine of the character described, the combination of a carrier having 25 a pocket provided with outlets at its opposite ends and adapted to receive the article to be trimmed, means for moving said carrier so as to cause the outlets of the pocket to be alternately arranged lowermost and 30 the article therein to slide successively in opposite directions therein toward the depressed ends of the pocket, means for limiting the movement of said article in the pocket toward the depressed ends thereof, 35 and means for trimming off the tips of the article in said pocket.

39. In a machine of the character described, the combination of a carrier adapted 40 to receive an article to be trimmed and provided with an outlet, means for moving said carrier forwardly, means for tilting said carrier so that the outlet end thereof is depressed, means for limiting the movement of said article in the carrier toward the depressed end thereof, means for severing that 45 tip of said article which has been depressed, and means for moving said limiting means out of the path of said article after the tip has been severed therefrom to permit said 50 tip to escape.

40. In a machine of the character described, the combination of a carrier adapted 55 to receive an article to be trimmed and provided with an outlet, means for limiting the movement of said article in the carrier toward said outlet, means for severing that tip of said article adjacent to said outlet, means for moving said limiting means out of the path of said article after the tip has 60 been severed therefrom to permit said tip to escape, and means for preventing the escape of the body of said article while said limiting means are shifted to permit the escape of said tip.

41. In a machine of the character de- 65 scribed, the combination of a carrier adapted to receive an article to be trimmed and having an outlet, means for moving said carrier forward, and also tilting the same, a cutter arranged at the depressed end of 70 said carrier and adapted to sever the tip from the body of said article, means for limiting the movement of said article toward the depressed outlet before the carrier reaches said cutter, and means for preventing the body of said article from moving toward said outlet after the tip has been severed by said cutter and while the carrier is still in its tilted position.

42. In a machine of the character de- 80 scribed, the combination of a carrier adapted to receive an article to be trimmed and having an outlet, means for moving said carrier forward, and also tilting the same, a cutter arranged at the depressed end of 85 said carrier and adapted to sever the tip from the body of said article, means for limiting the movement of said article toward the depressed outlet before the carrier reaches said cutter, and a retaining plate which is ar- 90 ranged in rear of the cutter in position to be engaged by the trimmed article while the carrier is still in a tilted position.

43. In a machine of the character de- 95 scribed, the combination of a carrier having a pocket provided with outlets at its opposite ends and adapted to receive an article to be trimmed, means for propelling said carrier and causing the outlets at opposite ends of its pocket to be arranged lowermost 100 alternately so that the article therein moves successively toward opposite ends of the pocket, means for limiting the movement of said article toward the depressed ends of the pocket, and means for severing the ends of 105 said article at the depressed ends of the pocket, said means which limit the movement of the article in the pocket the second time being constructed to clear said article after the end of the same has been severed 110 and while the pocket is still in its second position.

44. In a machine for treating articles, an article receiving pocket in which the article is longitudinally movable, means to move 115 said pocket to a plurality of positions and cause the article carried thereby to move successively in opposite directions therein with portions of its opposite ends projecting alternately beyond opposite ends of said 120 pocket, means for treating one end of said article while projecting beyond one end of said pocket and for treating the opposite end of said article when the last mentioned end projects beyond the other end of said 125 pocket.

45. In a machine for treating articles, an article receiving carrier in which the article

is movable longitudinally, means for causing the article to move successively toward opposite ends of said carrier, means for treating one end of said article when moved to the corresponding end of the carrier and for treating the opposite end of said article when the last mentioned end of the latter

is moved to the corresponding opposite end of the carrier.
